UNITED STATES PATENT OFFICE.

CARL J. LJUNGGREN, OF PROVIDENCE, RHODE ISLAND.

CLOSURE-LOCKING MEANS.

977,647.

Specification of Letters Patent.

Patented Dec. 6, 1910.

Original application filed September 2, 1908, Serial No. 451,444. Divided and this application filed April 15, 1910. Serial No. 555,561.

To all whom it may concern:

Be it known that I, CARL J. LJUNGGREN, a subject of the King of Sweden, residing at Providence, in the county of Providence and State of Rhode Island, have invented certain new and useful Improvements in Closure-Locking Means, of which the following is a specification.

My invention relates to closure locking means for gun breeches, vault doors, ports and manholes. The same is a division of my pending patent application Ser. No. 451,444 filed Sept. 2, 1908.

My invention is primarily purposed to avoid the necessity of the employment of screw threads upon the bearing surfaces of the closure member, and afford a maximum pressure resisting surface distributed in a manner to minimize the strain upon the structure.

Additional objects are simplicity and inexpensiveness of construction.

To the above enumerated ends essentially my invention consists in the novel construction of parts set forth in and falling within the scope of the appended claims.

In the accompanying drawings which constitute a part of this specification, Figures 1 and 2 are rear and side elevations respectively of my closure member, Fig. 3, a rear elevation of the stationary member, Fig. 4, a section on line $\alpha\alpha$ of Fig. 3, Fig. 5, a rear elevation of the closure member in engaged position within the orifice of the stationary member, and Fig. 6, a section on line yy of Fig. 5.

Similar letters of reference indicate similar parts throughout the views.

My invention, in its present embodiment, comprises a closure member A which is a plug, door, or block adapted to be seated in a stationary member B which is either a breech or jamb. The supporting, inserting, and rotating mechanism for the member A is familiar to the art, and hence herein omitted.

The closure member A comprises a sub-

stantially cylindrical body a provided intermediate its length with annularly arranged segments C interspaced equidistant from each other, each comprising a plurality of radially graduated stepped portions D, E, F.

The peripheries of the stepped portions comprise inclined bearing surfaces d , d' , e , e' , and f , f' , respectively extending from the sides of the segment inwardly, and converging in lines d^2 , e^2 , and f^2 , respectively, disposed centrally of the stepped portions. The end or radial faces d^3 , e^3 , f^3 of the stepped portions are non-inclined.

The receiving or stationary member or jamb comprises a collar B fixed in any suitable manner in the wall I whose outer and inner faces are at i and i^2 respectively. The collar incloses a substantially cylindrical orifice J of preferably reduced diameter at its front end to form an abutment K. The orifice has a circumferential series of radially graduated entrance openings L, M, N which merge into annularly arranged radially graduated channels or seats O, P, Q, respectively, having inwardly converging inclined side bearing faces o , o' , p , p' , and q , q' , and non-inclined radial end faces or abutments o^2 , p^2 , and q^2 respectively.

The parts A and B are interengaged thus. The former disposed as in Fig. 2 is introduced into the member B from right to left as viewed in Fig. 6, the stepped portions D, E, F registering in the channels L, M, N respectively. The member A is then turned in the direction of the arrow shown in Fig. 5 to bring the portions D, E, F into the seats O, P, Q respectively, with the inwardly converging faces d , d' , e , e' , and f , f' , in frictional contact with the bearing faces o , o' , p , p' , and q , q' , respectively; and the radial faces d^3 , e^3 , f^3 against the abutments o^2 , p^2 and q^2 respectively.

What I claim is,

1. In a device of the type set forth, the combination with a stationary member, of a closure body, and a segment upon the body

comprising radially graduated stepped portions, said stepped portions being provided with peripheral inclined inwardly converging bearing surfaces.

5. 2. In a device of the type set forth, the combination with a stationary member, of a closure body comprising radially graduated stepped portions, said stepped portions being provided with peripheral inwardly

inclined bearing faces converging in lines disposed centrally of the stepped portions.

In testimony whereof I have affixed my signature in presence of two witnesses.

CARL J. LJUNGGREN.
